(57) **ABSTRACT**

Provided is a voltage regulator having satisfactory transient response characteristics. Because a PMOS (25) and an NMOS (24) pass drain currents (charge and discharge currents with respect to gate of PMOS (26)) based on the square of voltage (ΔV) according to change (ΔI) in drain currents of NMOSs (16 and 17), a maximum value (I_{max}) of the charge and discharge currents becomes larger, transition time (t) of gate voltage of the PMOS (26) becomes shorter, and the transient response characteristics of the voltage regulator become better.

VOLTAGE REGULATOR WITH IMPROVED
TRANSIENT RESPONSE

BACKGROUND OF THE INVENTION

1. Field of the Invention

The present invention relates to a voltage regulator.

2. Description of the Related Art

A conventional voltage regulator is described. FIG. 4 is a circuit diagram illustrating a conventional voltage regulator.

NMOSs 46 and 47, PMOSs 48 and 49, NMOSs 53 and 54, a PMOS 52, and a PMOS 55 form a differential amplifier circuit. In the differential amplifier circuit, gates of the NMOSs 46 and 47 are input terminals while drains of the PMOS 55 and the NMOS 54 are output terminals. The PMOS 55 and NMOS 54 form a push-pull circuit. NMOSs 44 and 45 form a current mirror circuit and have constant current characteristics. A constant current circuit 58 and the NMOSs 44 and 45 function as a current supply means to the differential amplifier circuit.

Input voltage V_{in} which is power supply voltage is input to an input terminal 42. A PMOS 56 outputs to an output terminal 43 output voltage V_{out} which is controlled to be predetermined constant voltage based on the input voltage V_{in} and output voltage of the differential amplifier circuit. The output terminal 43 outputs the output voltage V_{out} which is controlled to be the predetermined constant voltage. The output voltage V_{out} of the output terminal 43 is input to a voltage divider circuit 57. The voltage divider circuit 57 divides the output voltage V_{out} and outputs divided voltage V_{fb} . The constant current circuit 58 supplies constant current I_{bias} to the differential amplifier circuit. A reference voltage circuit 59 applies reference voltage V_{ref} to the gate of the NMOS 46. The reference voltage V_{ref} and the divided voltage V_{fb} are input to the differential amplifier circuit. The differential amplifier circuit amplifies differential voltage V_{diff} between the reference voltage V_{ref} and the divided voltage V_{fb} , and outputs the output voltage V_{out} based on the differential voltage V_{diff} . The differential amplifier circuit controls the output voltage V_{out} to be the predetermined constant voltage by controlling gate voltage of the PMOS 56 such that the reference voltage V_{ref} and the divided voltage V_{fb} are equal to each other (see, for example, Japanese Patent Application Laid-open No. 2001-273042).

Here, characteristics of the PMOSs 48 and 49, the PMOS 52, and the PMOS 55 are the same, characteristics of the NMOSs 46 and 47 are the same, and a mirror ratio of the current mirror circuit of the NMOSs 53 and 54 is 1:1.

When the differential voltage V_{diff} between the reference voltage V_{ref} and the divided voltage V_{fb} is 0, gate voltage of the NMOS 46 and gate voltage of the NMOS 47 are the same, and drain current of the NMOS 46 and drain current of the NMOS 47 are the same. Therefore, the values of those drain currents and of drain currents of the PMOSs 48 and 49, the PMOS 52, and the PMOS 55 are the same, and values of drain currents of the NMOSs 53 and 54 are the same. Each drain current is half of drain current I_{tail} of the NMOS 45.

Next, the drain currents of the respective transistors are described. FIGS. 5A and 5B are graphs illustrating the drain currents of the respective conventional transistors.

FIG. 5A illustrates a relationship between the differential voltage V_{diff} and absolute values of the drain currents of the NMOSs 46 and 47 which are transistors in an input stage of the differential amplifier circuit. When the differential voltage V_{diff} is 0, the values of the drain currents of the NMOSs 46 and 47 are the same, and each of the drain currents is half of the drain current I_{tail} of the NMOS 45. When the differ-

2

ential voltage V_{diff} varies, the absolute value of the drain current of one of the NMOSs 46 and 47 increases, and the absolute value of the drain current of the other MOS decreases accordingly.

FIG. 5B illustrates a relationship between the differential voltage V_{diff} and absolute values of the drain currents of the PMOS 55 and the NMOS 54 (absolute values of charge and discharge currents with respect to a gate of the PMOS 56 which is an output transistor). When the differential voltage V_{diff} is 0, the values of the drain currents of the PMOS 55 and the NMOS 54 are the same, and each of the drain currents is half of the drain current I_{tail} of the NMOS 45.

When the differential voltage V_{diff} varies, the absolute value of the drain current of one of the PMOS 55 and the NMOS 54 increases, and the absolute value of the drain current of the other MOS decreases accordingly. A maximum value I_{max} of the drain currents (charge and discharge currents with respect to gate of PMOS 56) is the value of the drain current I_{tail} of the NMOS 45.

Power consumption of electronic equipment such as portable electronic equipment is sometimes reduced by switching an electronic circuit therein between two states: a standby state for operation with reduced power consumption; and a normal operation state other than the standby state. In such a case, power consumption of a voltage regulator for supplying power supply voltage to the electronic equipment may also be reduced.

However, in an ordinary voltage regulator, reduced power consumption results in inferior transient response characteristics.

SUMMARY OF THE INVENTION

The present invention has been made in view of the above problem, and an object of the present invention is to provide a voltage regulator having satisfactory transient response characteristics.

In order to solve the above problem, according to an aspect of the present invention, a voltage regulator is provided, the voltage regulator including: an input terminal to which input voltage is input; an output transistor for outputting to an output terminal output voltage controlled to be predetermined constant voltage based on the input voltage and output voltage of a differential amplifier circuit; the output terminal for outputting the output voltage; a voltage divider circuit to which the output voltage is input for dividing the output voltage and outputting divided voltage; a constant current circuit for supplying a constant current to the differential amplifier circuit; a reference voltage circuit for generating reference voltage; and the differential amplifier circuit having an input stage including transistors to which the reference voltage and the divided voltage are input, for passing charge and discharge currents with respect to a gate of the output transistor based on the square of voltage according to change in drain currents of the transistors in the input stage and controlling gate voltage of the output transistor such that the reference voltage and the divided voltage are equal to each other, thereby controlling the output voltage to be equal to the predetermined constant voltage.

According to the present invention, because the differential amplifier circuit passes the charge and discharge currents with respect to the gate of the output transistor based on the square of the voltage according to change in drain currents of the transistors in the input stage, a maximum value of the charge and discharge currents becomes larger, transition time

of the gate voltage of the output transistor becomes shorter, and transient response characteristics of the voltage regulator become better.

BRIEF DESCRIPTION OF THE DRAWINGS

In the accompanying drawings:

FIG. 1 is a circuit diagram illustrating a voltage regulator; FIGS. 2A and 2B are graphs illustrating drain currents of respective transistors;

FIG. 3 is a circuit diagram illustrating a voltage regulator;

FIG. 4 is a circuit diagram illustrating a conventional voltage regulator; and

FIGS. 5A and 5B are graphs illustrating drain currents of respective conventional transistors.

DETAILED DESCRIPTION OF THE PREFERRED EMBODIMENT

An embodiment of the present invention is described in the following with reference to the attached drawings.

First, a structure of a voltage regulator is described. FIG. 1 is a circuit diagram illustrating the voltage regulator.

The voltage regulator has a ground terminal 11, an input terminal 12, an output terminal 13, NMOSs 14 to 17, resistances 20 and 21, NMOSs 23 and 24, PMOSs 18 and 19, a PMOS 22, PMOSs 25 and 26, a voltage divider circuit 27, a constant current circuit 28, and a reference voltage circuit 29.

The constant current circuit 28 is provided between the input terminal 12 and a drain of the NMOS 14. A source of the NMOS 14 is connected to the ground terminal 11 while a gate of the NMOS 14 is connected to the drain of the NMOS 14 and a gate of the NMOS 15. A source of the NMOS 15 is connected to the ground terminal 11 while a drain of the NMOS 15 is connected to sources of the NMOSs 16 and 17. The reference voltage circuit 29 is provided between the ground terminal 11 and a gate of the NMOS 16. A drain of the NMOS 16 is connected to a drain of the PMOS 18. A gate of the NMOS 17 is connected to the voltage divider circuit 27 while a drain of the NMOS 17 is connected to a drain of the PMOS 19. A gate of the PMOS 18 is connected to a gate of the PMOS 19 while a source of the PMOS 18 is connected to the input terminal 12. A source of the PMOS 19 is connected to the input terminal 12. A resistance 20 is provided between the gate and the drain of the PMOS 18 while a resistance 21 is provided between the gate and the drain of the PMOS 19.

A gate of the PMOS 22 is connected to the drain of the PMOS 18, a source of the PMOS 22 is connected to the input terminal 12, and a drain of the PMOS 22 is connected to a drain of the NMOS 23. A gate of the NMOS 23 is connected to a gate of the NMOS 24, a source of the NMOS 23 is connected to the ground terminal 11, and the drain of the NMOS 23 is connected to the gate of the NMOS 23. A source of the NMOS 24 is connected to the ground terminal 11 and a drain of the NMOS 24 is connected to a drain of the PMOS 25. A gate of the PMOS 25 is connected to the drain of the PMOS 19 and a source of the PMOS 25 is connected to the input terminal 12. The voltage divider circuit 27 is provided between the output terminal 13 and the ground terminal 11. A gate of the PMOS 26 is connected to the drain of the PMOS 25, a source of the PMOS 26 is connected to the input terminal 12, and a drain of the PMOS 26 is connected to the output terminal 13.

The NMOSs 16 and 17, the PMOSs 18 and 19, the resistances 20 and 21, the NMOSs 23 and 24, the PMOS 22 and the PMOS 25 form a differential amplifier circuit. In the differential amplifier circuit, the gates of the NMOSs 16 and 17 are

input terminals and the drains of the PMOS 25 and the NMOS 24 are output terminals. The PMOS 25 and the NMOS 24 form a push-pull circuit. The NMOSs 14 and 15 form a current mirror circuit and have constant current characteristics. The constant current circuit 28 and the NMOSs 14 and 15 function as a current supply means to the differential amplifier circuit.

Input voltage V_{in} which is power supply voltage is input to the input terminal 12. The PMOS 26 which is an output transistor outputs to the output terminal 13 the output voltage V_{out} controlled to be predetermined constant voltage based on the input voltage V_{in} and the output voltage of the differential amplifier circuit. The output terminal 13 outputs the output voltage V_{out} . The output voltage V_{out} of the output terminal 13 is input to the voltage divider circuit 27. The voltage divider circuit 27 divides the output voltage V_{out} , and outputs divided voltage V_{fb} . The constant current circuit 28 supplies constant current I_{bias} to the differential amplifier circuit. The reference voltage circuit 29 generates reference voltage V_{ref} , and applies the reference voltage V_{ref} to the gate of the NMOS 16. The reference voltage V_{ref} and the divided voltage V_{fb} are input to transistors in an input stage of the differential amplifier circuit. The differential amplifier circuit amplifies differential voltage V_{diff} between the reference voltage V_{ref} and the divided voltage V_{fb} , and outputs to the gate of the PMOS 26 output voltage based on the differential voltage V_{diff} . The differential amplifier circuit controls the output voltage V_{out} to be the predetermined constant voltage by controlling gate voltage of the PMOS 26 such that the reference voltage V_{ref} and the divided voltage V_{fb} are equal to each other.

Next, an operation of the voltage regulator is described.

Here, characteristics of the PMOSs 18 and 19, the PMOS 22, and the PMOS 25 are the same, characteristics of the NMOSs 16 and 17 are the same, and a mirror ratio of the current mirror circuit of the NMOSs 23 and 24 is 1:1.

When the differential voltage V_{diff} between the reference voltage V_{ref} and the divided voltage V_{fb} is 0, gate voltage of the NMOS 16 and gate voltage of the NMOS 17 are the same, and drain current of the NMOS 16 and drain current of the NMOS 17 are the same. Because of the current mirror circuit, drain current of the PMOS 18 and drain current of the PMOS 19 are the same. Each drain current is half of drain current I_{tail} of the NMOS 15. Because voltage at a node A and voltage at a node B are the same, current does not pass through the resistances 20 and 21 between the node A and the node B. Therefore, the voltage at the node A, the voltage at the node B, and voltage at a node C are equal to one another. Here, gate-source voltages of the PMOSs 18 and 19, the PMOS 22, and the PMOS 25 are the same, and drain currents of the PMOSs 18 and 19, the PMOS 22, and the PMOS 25 are the same. Because current $I_{tail}/2$ passes through the PMOSs 18 and 19, the PMOS 22, and the PMOS 25, the differential amplifier circuit passes current $2I_{tail}$.

When output current transiently varies and the output voltage V_{out} becomes lower than the predetermined constant voltage, the gate voltage of the NMOS 17 becomes lower than the gate voltage of the NMOS 16, and the drain current of the NMOS 17 becomes smaller than the drain current of the NMOS 16 by $2\Delta I$. Here, the drain current of the NMOS 17 becomes smaller by ΔI while the drain current of the NMOS 16 becomes larger by ΔI . Because the values of the resistances 20 and 21 are the same, the voltage at the node C does not vary and gate voltages of the PMOSs 18 and 19 do not vary, and thus, the drain currents of the PMOSs 18 and 19 do not vary. Further, because of the current mirror circuit, the drain currents of the PMOSs 18 and 19 are the same. Therefore, the

above-mentioned current $2\Delta I$ passes from the node B to the node A. When the value of the resistances **20** and **21** is denoted by a resistance value R, because voltage drops across the resistances **20** and **21**, the voltage at the node B becomes higher by ΔIR , the gate-source voltage of the PMOS **25** becomes lower by ΔIR , the voltage at the node A becomes lower by ΔIR , and the gate-source voltage of the PMOS **22** becomes higher by ΔIR . Here, the PMOS **22** and the PMOS **25** operate in a saturation region, and the drain current of the PMOS **22** and the drain current of the PMOS **25** are in proportion to the square of the respective gate-source voltages. Therefore, the drain current of the PMOS **25** decreases in proportion to the square of ΔIR , and the drain currents of the PMOS **22** and the NMOSs **23** and **24** increase in proportion to the square of ΔIR . The drain current of the PMOS **22** effects push-pull operation of the PMOS **25** and the NMOS **24** via the current mirror circuit of the NMOSs **23** and **24**. Therefore, drain voltage of the PMOS **25**, drain voltage of the NMOS **24**, and the gate voltage of the PMOS **26** become lower, drain current (output current) of the PMOS **26** increases, and the output voltage V_{out} becomes higher.

When the output current transiently varies and the output voltage V_{out} becomes higher than the predetermined constant voltage, the gate voltage of the NMOS **17** becomes higher than the gate voltage of the NMOS **16**, and the drain current of the NMOS **17** becomes larger than the drain current of the NMOS **16** by $2\Delta I$. The above-mentioned current $2\Delta I$ passes from the node A to the node B. The voltage at the node B becomes lower by ΔIR , the gate-source voltage of the PMOS **25** becomes higher by ΔIR , the voltage at the node A becomes higher by ΔIR , and the gate-source voltage of the PMOS **22** becomes lower by ΔIR . The drain current of the PMOS **25** increases in proportion to the square of ΔIR , and the drain currents of the PMOS **22** and the NMOSs **23** and **24** decrease in proportion to the square of ΔIR . Therefore, the drain voltage of the PMOS **25**, the drain voltage of the NMOS **24**, and the gate voltage of the PMOS **26** become higher, the drain current (output current) of the PMOS **26** decreases, and the output voltage V_{out} becomes lower.

Next, the drain currents of the respective transistors are described. FIGS. 2A and 2B are graphs illustrating the drain currents of the respective transistors.

FIG. 2A illustrates a relationship between the differential voltage V_{diff} and absolute values of the drain currents of the NMOSs **16** and **17** which are transistors in the input stage of the differential amplifier circuit. When the differential voltage V_{diff} is 0, the values of the drain currents of the NMOSs **16** and **17** are the same, and each of the drain currents is half of the drain current I_{tail} of the NMOS **15**. When the differential voltage V_{diff} varies, the absolute value of the drain current of one of the NMOSs **16** and **17** increases, and the absolute value of the drain current of the other MOS decreases accordingly.

FIG. 2B illustrates a relationship between the differential voltage V_{diff} and absolute values of the drain currents of the PMOS **25** and the NMOS **24** (absolute values of charge and discharge currents with respect to the gate of the PMOS **26** which is an output transistor). When the differential voltage V_{diff} is 0, the values of the drain currents of the PMOS **25** and the NMOS **24** are the same, and each of the drain currents is half of the drain current I_{tail} of the NMOS **15**. When the differential voltage V_{diff} varies, the absolute value of the drain current of one of the PMOS **25** and the NMOS **24** increases, and the absolute value of the drain current of the other MOS decreases accordingly. A maximum value I_{max} of

the drain current (charge and discharge currents with respect to gate of PMOS **26**) is larger than the value of the drain current I_{tail} of the NMOS **15**.

Because a relatively large gate parasitic capacitance exists in the gate of the PMOS **26**, it takes predetermined transition time for transition of the gate voltage. When a transition width of the gate voltage is denoted by ΔV_g , the gate parasitic capacitance is denoted by C_g , and the maximum value of the charge and discharge currents with respect to the gate is denoted by I_{max} , transition time t of the gate voltage is calculated by the following equation:

$$t = \Delta V_g \times C_g / I_{max}$$

Because the transition width ΔV_g of the gate voltage is determined by the width of variation of the output current and the output voltage V_{out} and the gate parasitic capacitance C_g is determined by driving ability of the PMOS **26** and the thickness of a gate insulating film, when the maximum value I_{max} of the charge and discharge currents with respect to the gate becomes larger, the transition time t of the gate voltage becomes shorter, and transient response characteristics of the voltage regulator become better.

Because, in this way, the PMOS **25** and the NMOS **24** pass the drain current (charge and discharge currents with respect to gate of PMOS **26**) based on the square of the voltage (ΔIR) according to the change (ΔI) in drain currents of the NMOSs **16** and **17**, the maximum value I_{max} of the charge and discharge currents becomes larger, the transition time t of the gate voltage of the PMOS **26** becomes shorter, and the transient response characteristics of the voltage regulator become better. Then, in transition where the state of a load transitions, even when the output current transiently varies, the voltage regulator having the satisfactory transient response characteristics can operate normally, and the output voltage V_{out} of the voltage regulator is the predetermined constant voltage.

Further, because the transient response characteristics of the voltage regulator become better, the power consumption may be suppressed accordingly.

It is to be noted that, in FIG. 1, the constant current circuit and the NMOSs **14** and **15** are the current supply means to the differential amplifier circuit, but, as illustrated in FIG. 3, constant current circuits **32** and **33** and a resistance **31** may be the current supply means.

Further, the current mirror circuit of the NMOSs **23** and **24** may be a Wilson current mirror circuit or a cascode current mirror circuit with a transistor (not shown) added thereto.

What is claimed is:

1. A voltage regulator, comprising:
an input terminal to which input voltage is input;
an output terminal for outputting output voltage;
an output transistor provided between the input terminal and the output terminal;
a voltage divider circuit provided at the output terminal for dividing the output voltage and for outputting divided voltage;
a reference voltage circuit for outputting reference voltage; and
a differential amplifier circuit including a first input transistor having a gate to which the reference voltage is input and a second input transistor having a gate to which the divided voltage is input, for controlling the output transistor based on a square of voltage according to change in drain currents of the input transistors.
2. A voltage regulator according to claim 1, wherein the differential amplifier circuit comprises:
a constant current circuit;

a first transistor of a first conductivity type having a gate connected to the reference voltage circuit and a source connected to the constant current circuit;

a second transistor of the first conductivity type having a gate connected to the voltage divider circuit and a source connected to the constant current circuit;

a first transistor of a second conductivity type having a source connected to the input terminal and a drain connected to a drain of the first transistor of the first conductivity type;

a second transistor of the second conductivity type having a gate connected to a gate of the first transistor of the second conductivity type, a source connected to the input terminal, and a drain connected to a drain of the second transistor of the first conductivity type;

a first resistance having one end connected to the gate of the first transistor of the second conductivity type and another end connected to the drain of the first transistor of the second conductivity type;

a second resistance having one end connected to the gate of the second transistor of the second conductivity type and another end connected to the drain of the second transistor of the second conductivity type;

a third transistor of the second conductivity type having a gate connected to the another end of the first resistance and a source connected to the input terminal;

a third transistor of the first conductivity type having a gate, a source connected to a ground terminal, and a drain connected to a drain of the third transistor of the second conductivity type and the gate;

a fourth transistor of the first conductivity type having a gate connected to the gate of the third transistor of the first conductivity type, a source connected to the ground terminal, and a drain connected to a gate of the output transistor; and

a fourth transistor of the second conductivity type having a gate connected to the another end of the second resistance, a source connected to the input terminal, and a drain connected to the gate of the output transistor.

3. A voltage regulator according to claim 1, wherein the differential amplifier circuit comprises:

a constant current circuit;

a first transistor of a first conductivity type having a gate connected to the reference voltage circuit and a source connected to the constant current circuit;

a second transistor of the first conductivity type having a gate connected to the voltage divider circuit and a source connected to the constant current circuit;

a first transistor of a second conductivity type having a source connected to the input terminal and a drain connected to a drain of the first transistor of the first conductivity type;

a second transistor of the second conductivity type having a gate connected to a gate of the first transistor of the second conductivity type, a source connected to the input terminal, and a drain connected to a drain of the second transistor of the first conductivity type;

a first resistance having one end connected to the gate of the first transistor of the second conductivity type and another end connected to the drain of the first transistor of the second conductivity type;

a second resistance having one end connected to the gate of the second transistor of the second conductivity type and another end connected to the drain of the second transistor of the second conductivity type;

a third transistor of the second conductivity type having a gate connected to another end of the first resistance and a source connected to the input terminal;

a current mirror circuit having two terminals, one of the two terminals passing a current-mirror current based on drain current of the third transistor of the second conductivity type, another one of the two terminals passing a current, based on the current-mirror current, to a gate of the output transistor; and

a fourth transistor of the second conductivity type having a gate connected to the another end of the second resistance, a source connected to the input terminal, and a drain connected to the gate of the output transistor.
